UNITED STATES PATENT OFFICE.

OSCAR G. WEE, OF TOMAHAWK, WISCONSIN.

LIFTING-JACK.

1,300,067.

Specification of Letters Patent.

Patented Apr. 8, 1919.

Application filed May 29, 1918. Serial No. 237,292.

To all whom it may concern:

Be it known that I, OSCAR G. WEE, a citizen of the United States, residing at Tomahawk, in the county of Lincoln and State of 5 Wisconsin, have invented new and useful Improvements in Lifting-Jacks, of which the following is a specification.

This invention relates to new and useful improvements in lifting jacks and the principal object of the invention is to provide 10 simple and effective means for raising and lowering the movable part of the jack, said means permitting the movable part to be lowered with the lugs out of contact with 15 the ratchet.

Another object of the invention is to provide the jack with bolt cutting means, pipe clamping means and wire holding means.

Another object of the invention is to provide 20 a device of this character which is simple and durable in construction, reliable and efficient in operation and one which can be manufactured and placed upon the market at a minimum cost.

The invention also consists in certain other 25 features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several 35 views, and in which:—

Figure 1 is a side view of the invention.

Fig. 2 is an end view thereof.

Fig. 3 is a longitudinal section through the movable member.

Fig. 4 is a section on line 4—4 of Fig. 1.

Fig. 5 is a cross section on line 5—5 of Fig. 1, showing the means for detachably connecting the base to the ratchet bar.

Fig. 6 is a detail view.

As shown in these views the device consists 45 of the upright or ratchet bar 1 having the ratchet teeth 2 thereon. This bar has its lower end seated in the socket 3 in the base member 4 and said bar is removably held in said socket by means of the spring controlled latch 5 having its pointed end engaging with a hole 6 in said bar. By this means the base 50 may be detached when the device is to be used as a wire stretcher or whenever desired.

As will be seen from the drawings the ratchet

bar is of I-shape so as to provide a recess 7 on each side thereof.

The movable member 8 is provided with the guides 9, one on each side portion, for engaging the recesses 7 so as to prevent the 60 movable member from having a rocking movement on the ratchet bar and thus cause the wearing of the ratchet teeth by said teeth coming in contact with a part of the movable member. 10 is the operating handle pivoted in the movable member and provided with the pair of dogs 11 for engaging the ratchet teeth, said dogs being pivoted in the handle, and spring controlled as usual. Each dog is provided with a laterally extending lug 12 which 70 is adapted to be engaged by a cam member 13 pivoted on the pivotal pin of the handle. This cam member is provided with a cam part 14 for engaging with the lug on the holding dog and a double cam part 15 for engaging 75 with the lug on the lifting dog. The part 14 is formed by a substantially U shape recess in one side of the member at the center thereof while the part 15 is formed of a double curve adjacent the end of said member. This cam 80 member is operated by means of the plate 16 pivoted to one of the side parts of the movable member and having a lug 17 thereon engaging with a cam opening 18 in the cam member. This plate has an extension 19 85 which passes through an arc-shaped slot 20 formed in one of the side parts so that the said plate may be actuated from the exterior of the movable member. A spring 21 holds the cam member in its two positions with the 90 dogs in lifting position and in lowering position.

When the extension on the plate is moved to one end of the slot the dogs are moved to a position where they will raise the movable 95 part on the ratchet bar when the handle is operated. When the extension is moved to the other end of the slot the dogs are so positioned that the movable member will be lowered when the handle is operated. In this 100 position of the dogs and when there is no load on the jack the handle may be raised to its highest position to throw both dogs out of engagement with the teeth so that the movable member may be lowered quickly. As 105 before stated the guides operating in the recesses or grooves will prevent any side play of the movable member and thus protect the ratchet teeth from wear.

22 is the handle member bolted to the top 110

of the ratchet bar. This handle member is provided with a groove 23 adjacent one edge of the bar in which is removably secured one part 24 of a bolt cutter. The other part 25 5 of this bolt cutter is removably secured in the movable member so that when the member is raised the cutting edges of said parts will coincide to cut a bolt. Pipe clamping jaws 26 are removably secured to said movable member and the handle member adjacent the opposite or ratchet edge of the ratchet bar. 27 indicates one member of a wire stretcher carried by the handle member while the other member 28 of the stretcher 10 is carried by the movable member. These wire stretching devices may be made in any suitable manner.

It is thought from the foregoing description that the advantages and novel features 15 of my invention will be readily apparent.

I desire it to be understood that I may

make changes in the construction and in the combination and arrangement of the several parts, provided that such changes fall within the scope of the appended claim.

25

What I claim is:—

A lifting jack comprising a ratchet bar having ratchet teeth thereon, a movable member embracing said bar, a handle pivoted in said movable member, a pair of dogs carried by said handle and engaging the teeth, a lug on each dog, a cam member having a substantially U shaped recess in its side engaging one lug and a double curve adjacent its end engaging the other lug, said cam member having a cam opening provided with curved walls, an operating lever having a concentric part and a pin on said part engaging said opening.

30

In testimony whereof I affix my signature.

35

OSCAR G. WEE.
